STOCK CONTROLLED MECHANISM

Carroll E. Miller, Windsor, Vt., assignor to Cone
Automatic Machine Company Inc., Windsor,
Vt., a corporation of Vermont

Application December 9, 1937, Serial No. 178,933

13 Claims. (Cl. 29—62)

In the running of machines which perform operations on successive lengths or pieces of work which are successively fed into operating position, it is important that each length or piece be fed to a definite position before the operations 5 are commenced thereon in order that such operations shall be performed in the proper relation to the dimensions of the lengths or pieces. In many cases the feeding of such lengths or pieces 10 is accomplished by some type of feeding means either yieldable or frictional ordinarily adjusted to effect a slight over-feed in an effort to avoid the possibility of under feed, the work being fed against a positive stop at or before the end of 15 the normal feeding action so as to definitely position the length or article. With such a mechanism it may occasionally happen that the work is prevented from actually reaching the stop and so is not in proper position to have the machine 20 operations performed thereon. Under such circumstances the article would be improperly operated upon, and should a series of tools be in operation with a work feeding action between them, any failure to feed to the desired extent 25 would result in improper relations between the tooling of the successive operations, spoiling the work and possibly, also, causing breakage of the tools or other parts.

In accordance with the present invention, 30 therefore, the failure of the stock to reach the stop when such feed occurs, results in stopping the machine automatically, so that any subsequent operations after the feed are not performed until after the work has been placed in 35 proper position. As shown and described more in detail hereinafter, this may be accomplished by the employment of a stock stop so formed that engagement of the stock thereon after a feeding action has taken place is essential for 40 continued operation of the machine.

For a more complete understanding of this invention, reference may be had to the accompanying drawings in which the invention is shown as applied to a multiple spindle automatic 45 lathe, though it will be evident that it is not limited to a machine of this particular type. In these drawings,

Figure 1 is a side elevation of the multiple spindle automatic lathe embodying the invention.

Figure 2 is a section to a larger scale on line 2—2 of Figure 1.

Figure 3 is a diagrammatic view of the fluid pressure and electrical stop mechanisms, the work being shown as incompletely fed toward 55 the stop.

Figure 4 is an end elevation of certain of the mechanism shown in Figure 3.

Figure 5 is a section to a larger scale through the spindle nose and stock stop, the stock being shown in properly fed condition.

Figures 6 and 7 are detail sections showing a stock stop suitable for tubular work, the stock being shown in incomplete and properly fed positions, respectively.

Referring first to Figures 1 and 2, there is 10 shown a multiple spindle automatic lathe of the well known Cone type, such as exemplified, for example, in the Cone Patent No. 1,271,540 granted July 9, 1918. This machine, as shown, comprises a base 1 having upright portions 2 and 3 15 adjacent to opposite ends and a top horizontal frame member 4 bridging the upper ends of the portions 2 and 3. Within the portion 2 is positioned a drum or turret shown at 5 in Figure 2 which carries a plurality of rotary work spindles 20 provided with work-engaging chucks 6 at their inner ends for the reception of continuous lengths of bar stock such as 7. This stock may be operated upon by various tools such as 8 positioned at various operating stations to which the stock carried by the several spindles is moved in sequence in the usual and well known manner.

The frame portion 4 carries a cam shaft 10, 30 which through suitable connections, as is well known, controls the indexing of the turret and the operation of the various tools which are fed in toward the work, such operating mechanism being partly shown in Figure 2. For feeding the side tools 8 the upper and lower rock arms 12 and 14 on each side may be employed, these having actuating bars 15 and 16 which are moved and controlled by cams (not shown) on the cam shaft 10.

At one of the stations, shown in Figure 2 as 40 the upper left hand station, the stock is fed into position for a start of the various machining operations and from this station it is passed in succession to the other stations, the work being finally cut off and discharged from the machine in time for the next stock feeding operation at 45 the first station in accordance with usual practice. The stock feed may be produced by any well known means which may be that shown in the Cone Patent No. 2,045,070 of June 23, 1936, wherein the stock is fed by forward motion of 50 the stock feeding tube, such as is shown in Figure 5 at 20. The stock passes through this feed tube and at its forward end the feed tube is provided with a spring gripper shown at 21 which frictionally engages the stock. In order that 55

the stock may be fed to the desired extent, it is the usual practice with feeding mechanisms of this type, to provide an extent of feed motion of the gripper 21 somewhat greater than that which the stock should have, the stock being positively stopped when it has been fed to the desired distance by impingement on a stock stop, such a stop being shown at 25 in Figures 1, 2, 3 and 5. The feeding action is resilient in order to permit the feed motion of the stock to stop when it contacts with the stock stop and also to prevent damage to the parts should any obstruction prevent the full feeding action of the stock. When the stock has been so fed, it is gripped in the chuck 6. As shown in Figure 5, this chuck may be of the collet type, the work spindle 30 having at its forward end a tapered opening 31 which cooperates with a plurality of spring fingers 32 matingly tapered externally and formed to grip the stock therebetween when the collet is moved rearwardly. This motion is effected through the axial motion of a sleeve 33 which is slidably within the spindle 30 and which surrounds the stock feed sleeve 20.

The stock stop 25 is arranged to be moved into stopping position just before the feed is to take place and after the feed is retracted out of the way so that tools can operate on the projecting portion of the stock without hindrance from the stop. As shown in Figure 2, this stop is carried at the outer end of a lever 40 carried by a rock shaft 41. This lever 40 is provided with an oppositely extending portion 42 which is connected through a link 43 to a cam follower arm 44 fulcrumed at 45. This arm 44 has intermediate its ends a cam follower roll 46 journaled thereon, which contacts with an edge cam 47 carried by cam shaft 10, so that when the stock is to be fed, the arm 42 is allowed to move from its full line position shown in Figure 2 to the dotted line position, permitting the stock stop 25 to lower into position opposite to the work spindle in the loading station. After the stock has been fed and gripped by the chuck 6, the stop 25 is retracted to the full line position by the action of the cam 47.

In accordance with the present invention means are provided by which the engagement of the stock against the stop, when the stop is in operative position, so conditions the operating mechanism of the machine that the operation proceeds, but should the stock fail to reach its fully fed position as determined by the stock stop, the machine stops. To this end the mechanisms shown in Figures 3, 4 and 5 have been provided. The machine as a whole is driven as from an electric motor 50 shown in Figures 1 and 3. While this motor may be of any suitable type, it is shown as of the three-phase induction type its energy supply being controlled through a main switch indicated generally at 51 and including switch elements 52 for each of the three phases, and a holding coil 53, which, when energized, holds the switch closed. This holding coil is connected to one of the phases, as 54, of the supply at one end through the lead 55 and at its other end connected through the switch 550 and the lead 56 with one pole of the starter switch 57. The other pole of this switch 57 leads through a line 58 with the stop switch 59 and through a lead 60 with one pole of a normally closed switch 61, and a normally open switch 62. The opposite poles of these switches 61 and 62 are connected through the lead 65 with the return line of the switch 52 and thus to the phase line 54 through

the overload switch 63. The switches 61 and 62 are therefore arranged in parallel, and the switch 61 being normally closed, normally completes the circuit through the coil 53 when the starting button 57 is closed, so that the motor 50 is in operation. The lead 58 is connected through lead 64 with the switch 550 so as to cut out the starter switch 57 when the main switch 51 is closed.

At about the time in each cycle of the machine when the stock is to be fed, this normally closed switch 61 is opened and held open for a predetermined period, this being accomplished as shown by a cam pin 70 carried by a disk 71 secured to the rear end of the cam shaft 10, which depresses the switch arm 72 and moves the switch contact into its open position indicated at 73. This opening of the switch 61 would, unless the switch 62 were closed at that time, result in de-energizing the motor 50 and stopping the machine. However according to this invention, means are provided so that if the stock when fed moves to its fully fed position, the switch 62 will have been closed, and held closed during the time that the switch 61 is open. Means for accomplishing this may be as follows.

The stock stop 25 is provided with a fluid passage 80, which may open out on its forward face as at 81, this passage being sufficiently small and in alinement with the stock S when the stop is in its stopping position so that the impingement of the stock against the stop closes off the otherwise open end of the passage 80. Fluid such as oil or the like is supplied to the passage 80 as through a flexible pipe 82 from a line 83 which is connected into a fluid pressure operated mechanism at 84, this in turn, being supplied with fluid through a pipe 85 from a pump 86. Interposed between the pump 86 and the mechanism 84 is a relief valve 87 and a throttle valve 88, the valve 88 determining the rate of flow and the relief valve 87 determining the maximum pressure which may be maintained within the pipe 85, the fluid pressure mechanism 84, the pipe 83 and the fluid passage 80 in the stock stop. When the stock is fed into its proper position and closes off the outlet from the passage 80, continued operation of the pump causes a pressure to be built up within the fluid pressure pipes and passages and this acting on a plunger 90 within a cylinder 91 of the mechanism 84 presses this plunger 90 outwardly against the pressure of a spring 92 and into contact with the switch arm 93 of the normally open switch 62 so as to close this switch as shown in dotted lines in Figure 3. Thus when the switch 62 has been closed and held closed by the pressure of the fluid within the cylinder 91, opening of the switch 61 does not act to shut off the power to the motor 50, which is then energized through the switch 62. Continued rotation of the motor continues the rotation of the cam shaft and thus the rotation of the disk 71 so that the pin 70 passes by the switch arm 72 and allows the normally closed switch 61 to return to closed position. Subsequent removal of the stock stop from its stopping position which permits the switch 62 to again open has no effect to stop the operation of the machine. Should the stock fail to reach its fully fed position, however, the fluid pressure passage 80 will remain open, no pressure will be built up back of the plunger 90 and the switch 62 will fail to be closed, so that when the cam shaft 10 has rotated sufficiently for the pin 70 to open the switch 61, the motor 50 will become de-energized and the machine will stop. Thus the position of the plunger 90 is respons-

sive to whether or not the stock has reached its fully fed position at each feeding action, and means actuated by the response of the plunger 90 then determines whether or not the machine continues to operate to perform the subsequent machining operations.

In Figures 6 and 7, a modified construction of stop is illustrated which is particularly suitable for use with tubular stock, since tubular stock 10 would permit the escape of fluid under pressure from the fluid pressure passage 80 of the stop illustrated in Figures 3 and 5, even though the stock were fed to fully fed position. Referring to these figures, the stop 250 has a fluid passage 80a 15 extending through its body portion 251 and opens out through an end face thereof at 252. An abutment 253 is supported by the body portion 251 for movement toward and from the face 252. As shown it is supported from the body portion by means of headed pins 254 which are secured as by riveting in the abutment 253 and which are slidably guided through suitable holes in the body 251, the heads 255 riding in counterbored portions 256 of these holes.

25 When the stock is not in contact with the abutment plate 253, fluid under pressure within the passage 80a may escape freely between the body and the plate, while when the stock is in fully fed position, as shown in Figure 7, the abutment plate 30 253 is held up against the face 252 of the body portion and closes off this fluid pressure passage 80a, this resulting in a building up of pressure which actuates the plunger 90 and closes the normally open switch 62 when the stock is fed.

35 While tubular stock is shown in Figures 6 and 7, it, of course, will be apparent that this stop construction could be used with bar stock as well as with tubular stock.

In order to facilitate the manufacture of the stock stop, its body portion 251 may be externally threaded for engagement within an internally threaded socket in its supporting arm 40 and held in place as by one or two lock nuts 261. The body portion may be provided with a circumferential groove to provide an annular passage 262 45 communicating through the passage 263 with the passage 80 or 80a, and the arm 40 may be provided with a threaded socket 264 for reception of the end of the pipe 82 which may be secured 50 therein through a suitable union shown at 265 in Figures 3 and 5.

It will be evident, of course, that where individual articles are to be fed in place of portions of a continuous stock, the action may be precisely 55 the same as that herein described, with the exception of the use of a feeding mechanism suitable for individual pieces rather than for bar stock as shown.

From the foregoing description of certain embodiments of this invention, it will also be evident that other changes and modifications may be made without departing from the spirit or scope of this invention as defined by the appended claims.

65 I claim:

1. The combination with means for feeding stock to be worked upon toward a predetermined position, means for defining the fully fed position of said stock, and means for operating on the stock so fed, of means responsive to the position of said stock with relation to said defining means, means for controlling said operating means, and periodically actuated means causing said controlling means to be controlled by the 70 response of said responsive means, such response

corresponding to failure of the stock to reach a fully fed position acting to stop said operating means.

2. The combination in a machine having means for feeding stock to be worked upon toward a predetermined position, means defining a fully fed position of said stock, means for operating on the stock so fed, and means for driving said machine, of means responsive to the position of said stock with relation to said defining means for supplying energy to said driving means, means independent of said responsive means for supplying energy to said driving means, and means acting periodically to render said independent energy supplying means inoperative during which time said responsive means determines such supply, said responsive means being conditioned by failure of said stock to reach fully fed position to interrupt said responsive supply, whereby on failure of said stock to reach fully fed position the machine stops on the next succeeding actuation of said periodically acting means.

3. The combination with means for feeding stock to be worked upon toward a predetermined position, means defining a fully fed position of said stock, means for operating on the stock so fed, and means for driving said operating means, of a pair of means arranged in parallel and controlling the supply of power to said driving means, one of said controlling means being normally in power-supplying condition and the other controlling means being in power-denying position, means effective for a period after each feeding action to condition said one controlling means to deny power, means responsive to the position of said stock with relation to said defining means, and means controlled by said response during said period to condition said other controlling means to supply power only when said stock has been fed in the previous feeding action fully to 40 said predetermined position.

4. The combination with means for feeding stock to be worked upon toward a predetermined position, a stock stop movable from and to a position in the path of feed of said stock, means for moving said stop to present it in stopping position during the stock feed and then to retract said stop, means for operating on stock so fed, means operatively connected to said stop and responsive in one manner when stock is in fully fed engagement with said stop and in another manner when said stock is out of such engagement, and means controlled by such response when said stop is in stopping position for energizing said operating means only when such response is that produced by operative engagement of said stock with said stop.

5. The combination with means for feeding stock to be worked upon toward a predetermined position, means for operating on stock so fed, and an electric motor for driving said operating means, of a pair of controlling switches for said motor arranged in parallel, one of said switches being normally open and the other of said switches being normally closed, means effective 60 at each stock feeding action to close and hold closed for a period said normally open switch but only when said stock has been fully fed to said predetermined position, and means acting at each stock-feeding action to open and hold open said normally closed switch for a time during said first-mentioned period, whereby said operating means fails to operate following an incomplete feeding of the stock to said predetermined position.

6. The combination with means for feeding stock to be worked upon toward a predetermined position, a stop against which the stock may be fed to define said position, and means for operating on work so fed, of means responsive in one manner to the operative engagement of stock against said stop, and means controlled by said responsive means for preventing subsequent operation of said operating means except when said one manner of response has been effected at the last succeeding feed of said stock.

7. The combination with means for feeding stock to be worked upon toward a predetermined position, a stop against which the stock may be fed to define said position, and means for operating on work so fed, of fluid pressure actuated means responsive in one manner to the operative engagement of said stock against said stop, and means controlled by said fluid pressure actuated means for preventing subsequent operation of said operating means except when said one manner of response has been effected at the last succeeding feed of said stock.

8. A machine comprising means for periodically feeding stock to be operated upon toward a predetermined position, a stop against which the stock may be fed to define said position, said stop having a fluid passage therethrough closed when the stock is in fully fed position with respect thereto, means for operating on stock after each feeding action, and means effective to prevent subsequent action of said operating means when said fluid passage has not been closed during the next preceding stock feed.

9. A machine comprising means for periodically feeding stock to be operated upon toward a predetermined position, a stop against which the stock may be fed to define said position, said stop having a fluid passage therethrough closed when the stock is in fully fed position with respect thereto, means for supplying fluid to said passage to build up pressure when said passage is closed, a fluid pressure actuated means operatively connected to said passage, and means de-

pendent on the actuation of said fluid pressure means at each feeding actuation of the stock for producing subsequent operation of said operating means.

10. A machine comprising means for periodically feeding stock to be operated upon toward a predetermined position, a stop against which the stock may be fed to define said position, said stop having a fluid passage therethrough closed when the stock is in fully fed position with respect thereto, means for supplying fluid to said passage to build up pressure when said passage is closed, a fluid pressure actuated means operatively connected to said passage, an electric motor for actuating said operating means, a pair of controlling switches for said motor arranged in parallel, means automatically opening and there holding one of said switches for a time at each feed actuation, and operative connections for closing and holding closed the other of said switches by the actuation of said fluid pressure actuated means during the time said one switch is open.

11. A stock stop having a fluid passage therein, and a portion for engagement with stock fed thereagainst, said stop including means causing pressure of stock against said portion to close said passage.

12. A stock stop comprising a member having a face against which a face of stock to be stopped may be engaged, said member having a fluid passage opening through said member face within the area of said stock face in position to be closed off when the stock engages said member.

13. A stock stop comprising a member having a fluid passage opening out at one face thereof, and an abutment carried by said member for motion toward and from said face, said abutment having an inner face closing off said passage when in engagement with said face, and being positioned to be pressed into such engagement by stock fed against its outer face.

CARROLL E. MILLER.
